SHOE QUARTER MOULDING APPARATUS

William F. Herlihy, Haverhill, Mass.

Application January 24, 1945, Serial No. 574,427

1 Claim. (Cl. 12—97)

1

This invention pertains to the manufacture of footwear, and relates more especially to apparatus for moulding the quarter portion of an assembled shoe upper including the forepart, in preparation for lasting the upper.

The more usual practice in shoe making is to impart the desired shape to the quarter portion of the shoe upper by the application of lasting pull, thereby to conform the quarter to the rear part of the last, but in the very finest shoe making and in instances where the quarter is of stiff, heavy or other material which is difficult to shape, it has been proposed to subject the quarter portion of the upper to a moulding operation (similar to that used in the manufacture of moulded counters) prior to the lasting operation. While it is possible thus to mould the quarter portions of shoes of certain types by the employment of ordinary counter moulding apparatus, in particular shoes of the open shank type, it is very difficult, if not impossible, to mould shoe uppers having full vamps or a small opening at the top by means of the ordinary counter moulding devices.

Counter moulding apparatus of the usual type includes a rigid male die or plug whose upper part is shaped to the desired contour of the inside of the moulded counter, and a vertically movable head having a pair of relatively movable wings which collectively constitute the female die and which are forced toward each other as the head descends toward the plug, thereby to compress and form the counter to the shape of the dies. This plug is usually an integral casting comprising a foot or attaching portion, a vertical post, and the die proper at the upper end of the post. Since the plug is of some considerable height and subjected to extremely heavy stresses, it has been customary to make the post of substantial thickness from front to rear, for example a front-to-rear thickness of approximately two inches. Usually this supporting portion or post is of rectangular section, and since the upper portion or shaping part of the plug is usually approximately three inches thick from front to back, and of a vertical depth to accommodate counters having long shank extensions there is little clearance below the counter shaping portion of the plug for the reception of the forepart portion of an assembled shoe upper when the device is used for moulding the quarter portion of the assembled shoe upper. Since the upper part of the plug is curved to the contour of the back seam of the upper, the forepart of the upper (when the quarter of a shoe is being moulded)

2

tends to swing rearwardly, but such swinging of the forepart of the upper is interfered with by the lower part or post portion of the plug so that the upper is thereby cramped and may be torn if subjected to the moulding pressure. To avoid this, the prior practice in dealing with open shank shoes is to bend the forepart of the upper rearwardly and to slip it over the plug so that the toe portion of the upper lies rearwardly of the post portion of the plug. When thus positioned it is possible to apply the moulding pressure without danger of damage to the shoe, although this operation of flexing the upper rearwardly and passing the plug through it preparatory to the moulding operation and the subsequent pulling of the upper off from the plug, is troublesome and time-consuming. On the other hand, if the shoe upper be of the type having a high vamp and small top opening, it is impossible thus to pass the plug through the upper and thus the moulding of the quarters of such shoes by the usual counter moulding apparatus is very difficult and indeed in many cases impossible of performance.

25 The principal object of the present invention is to provide improved moulding means for use in moulding the quarters of shoe uppers, and in particular shoe uppers having high vamps and small top openings. Other and further objects 30 and advantages of the invention will be pointed out in the following more detailed description and by reference to the accompanying drawings wherein

Fig. 1 is a fragmentary more or less diagrammatic front elevation of a counter moulding machine of a well-known type, but embodying a novel plug made in accordance with the present invention;

Fig. 2 is a side elevation, illustrating a plug 40 of the usual prior type and showing the arrangement of a shoe upper of the open type on said plug preparatory to moulding;

Fig. 3 is a similar side elevation of the improved plug of the present invention indicating the position of the shoe upper on this plug during the moulding operation; and

Fig. 4 is a front elevation of the plug shown in Fig. 3.

Referring to the drawings, the numeral 1 designates the base portion of a counter moulding machine of conventional type. On this base portion is mounted a holder 2 which is designed to receive the lower part or foot 3 of the counter moulding plug. In accordance with the present invention this plug, as illustrated in Figs. 3 and

4, comprises the upper, head or die portion 4, which is externally shaped to constitute the internal die for shaping the inside of the quarter of the shoe. This head portion 4 is carried by a post 6 which, in the simplest construction is integral with both foot 3 and head 4 of the plug, the plug being made, for example, by first casting it in a single block and then turning down the post 6 to the desired dimensions. As above noted, the front-to-rear dimension of the head portion 4 of the plug, that is to say, the distance between the vertical front face 9 and the rear face 10, may approximate three inches, this being a usual dimension to provide the desired external contour for moulding shoe quarters of a given range of sizes. In accordance with the present invention the post 6 is of a diameter substantially less than the front-to-rear thickness of the head, for example, the stem or post portion 6 may approximate one and one-half inches in diameter and the axis of this stem or post portion is so relatively located as respects the surface 9 that the forward element 7 of the post is spaced rearwardly a distance of approximately one inch from the plane of the vertical front surface 9. As illustrated in Fig. 3, the distance from the shoulder 11, at which the surface 9 terminates, to the lower end of the stem 6, approximates three inches.

As contrasted with this new arrangement the old or usual plug, as illustrated in Fig. 2, having the foot 3^a and the head 4^a, comprises a post or stem 6^a, of rectangular transverse section, approximately two inches in thickness from front to rear and approximately one and one-half inches in transverse dimension.

In the old device, the post 6^a is so short that the distance from the shoulder 11^a to the lower end of the post approximates only two inches. It is thus manifest that with the new arrangement there is a very substantial clearance space beneath the shoulder 11 and forwardly of the foremost element 7 of the post 6, whereas in the prior construction, as shown in Fig. 2, this clearance space is very much smaller.

By reason of this small clearance space in the arrangement of Fig. 2, it is necessary, when moulding a shoe quarter S, to bend the quarter and dispose its forepart rearwardly of the post, as indicated in broken lines in Fig. 2. On the other hand, when moulding a shoe quarter by the employment of the new arrangement, as shown in Fig. 3, it is possible to dispose the forepart of the shoe upper S within the clearance space beneath the shoulder 11 and without necessitating the passage of the plug through the quarter preparatory to moulding, as is required in the arrangement of Fig. 2. It is thus not only possible to mould the quarter of an open shank shoe without passing the plug through the quarter, but also to mould quarters in which the top opening is too small to permit such passage of the plug. Thus this new construction not only facilitates the moulding of open type uppers but also the moulding of uppers which heretofore could not be moulded at all by the use of usual counter moulding mechanism.

While as above suggested the plug may be of integral construction, it is contemplated that the post 6 may be of a material different from that of the head 4 and the foot 3, for example, the post 70

6 may be of steel, while the head portion 4 and the bottom portion 3 may be castings. By making the post 6 of stronger material, it is possible still further to decrease its transverse dimensions and thus to provide even greater clearance space than that above suggested. In this connection it may be noted that by making the post 6 of circular transverse section the clearance space beneath the shoulder 11 is not only increased directly forward of the axis of the post but also at the sides of the post, since the circular contour of the post avoids the rear corners found in the usual plug, thus providing additional space at opposite sides of the plug for the accommodation of the forepart 15 of the upper. While a post 6 of circular transverse section is desirable, it is evident that by the use of extremely strong material such as some of the alloy steels, an acceptable post of other than circular transverse section may be provided, 20 having the requisite strength and stiffness, and which would occupy even less space either from front to rear or transversely than the circular post here illustrated, and it is contemplated that all such modifications affording the desired clearance space for the accommodation of the forepart 25 of the upper are to be considered as within the scope of the present invention as defined by the annexed claim.

I claim:

30 Apparatus for use in molding the quarter portion of an assembled shoe upper including a forepart, said apparatus being in general like a conventional counter-moulding machine and capable of exerting pressure sufficient to mould and 35 to flange shoe counters and wherein the quarter portion of the shoe upper is shaped by the combined action of a unitary fixed male die or plug and a female die comprising a pair of relatively moveable wings, the male die being mounted upon 40 a fixed rigid post and the female die being carried by a head which goes toward and from the male die in a rectilinear path, the male die or plug having a substantially vertical front face characterized in that the post is of circular horizontal section and of a diameter not substantially exceeding one and one-half inches and of a length of at 45 least three inches below the lower edge of the vertical face of the male die or plug, said front vertical face being disposed in a plane which is approximately one inch in front of the forward vertical element of the post, thereby providing clearance below the male die or plug for the accommodation of the forepart portion of the shoe upper while the quarter portion of the upper is 50 being moulded.

WILLIAM F. HERLIHY.
